UNITED STATES PATENT OFFICE

HERMAN C. LINN, OF CLEVELAND, OHIO, ASSIGNOR TO WILLIAM F. RAWLINGS, OF CLEVELAND, OHIO

VACUUM-CLEANER APPARATUS

Application filed December 16, 1926. Serial No. 155,279.

This invention relating as indicated to a vacuum cleaning apparatus is more particularly directed to an improved vacuum cleaning device for use in motor vehicles wherein 5 the suction existing in the intake manifold of the engine is utilized to create the vacuum.

The primary object of the invention is to provide a cleaning or dirt separating chamber having a connection to such engine intake 10 manifold and another connection in the form of a flexible tube to which is attached a suction nozzle. Preferably the chamber and its 15 connections are formed to be mounted directly upon the vehicle in an inconspicuous position such as under the instrument board or within the engine chamber on the front side of the cowl board. A further object is to construct the chamber of a transparent material so as to permit inspection of the interior 20 thereof and to provide a detachable connection upon the chamber proper whereby the same may be easily removed from its mounting independently of the intake and flexible hose connections.

25 A further object of the invention is to provide within the chamber a cleaning agent which not only prevents any dirt from being drawn therethrough into the intake manifold but which maintain substantially constant the velocity of the inrushing air during 30 the cleaning process. To the accomplishment of the foregoing and related ends, said invention, then, consists of the means herein-after fully described and particularly pointed 35 out in the claims.

The annexed drawing and the following description set forth in detail certain mechanism embodying the invention, such disclosed means constituting, however, but one 40 of the various mechanical forms in which the principle of the invention may be used.

In said annexed drawing:—

Fig. 1 is a sectional view through a preferred embodiment of the invention showing 45 the cleaning chamber mounted on the front side of the cowl board of an automobile; Fig. 2, a detail view in perspective of one of the dirt filtering elements; Fig. 3, a longitudinal section through the suction nozzle and one 50 end of its flexible hose connection; Fig. 4,

a sectional view taken on line 4—4 of Fig. 3; and Fig. 5 is a detail view of a locking ring employed in the present construction.

As indicated in the accompanying drawing, the present illustrated embodiment of 55 the invention about to be described consists of a vacuum cleaning device adapted to be permanently mounted upon a motor vehicle. It will be of course be obvious that the invention is capable of being incorporated in 60 other types of vacuum cleaning apparatus than one specifically constructed for use in automobiles.

Referring to Fig. 1, the engine is indicated at 10, the intake manifold thereof at 110 and 65 the cowl board of a vehicle at 12. A bracket 13 providing an apertured flange 14 is permanently secured to the board 12 by suitable bolts 15. The underside of the bracket is 70 formed with an annular recess 16 in which is receivable the upper end of a cleaning or dirt separating chamber 17 to be presently described. Communicating with such annular recess 16 through a threaded hole 18 in the bracket 13 is a connection 19 here shown as a 75 short pipe nipple to which is attached one end of a conduit 20. The other end of such conduit is attached through a shut-off valve 21 to the intake manifold 110, such valve being provided with a handle or thumb screw 22 for 80 manual operation.

The recess 16 referred to above is internally screw threaded and the upper end of the cleaning chamber is formed with external screw threads 24 whereby the latter member 85 may be quickly attached to or detached from the supporting bracket 13. A thumb screw 25 may be employed as shown to lock the chamber against turning in the bracket. A packing washer 26 is inserted between a flange 27 90 on the chamber 17 and the lower edge 28 of the flange portion surrounding the recess 16 to establish an air-tight joint between the recess and the interior of the chamber.

Provided in the flange 14 is a second 95 threaded hole 29 which is arranged centrally of the recess 16 and fixed in the upper portion thereof is a pipe nipple 30. In the lower end of said hole is screwed a depending tube 31, 100 the same extending interiorly of the chamber

17. To the pipe 30 is attached one end of a flexible hose 32 which carries at its outer end a vacuum nozzle 33.

As has been previously stated, my invention contemplates the provision of a cleaning or dirt separating agent to be interposed in the vacuum line of the present device which serves both to remove the dirt from the air drawn through the conduit 32 to the intake manifold and to regulate or maintain constant the velocity of the air passing through the cleaning chamber. The vacuum is created in the chamber 17 by the connection 20 to the intake manifold 110 of the vehicle engine and the air drawn through the flexible hose 32 is conducted first through the cleaning agent before entering the conduit 20. Attached to the lower end 35 of tube 31 is an annular head 36 which is adapted to fit within the upper end of a cylinder 37. An expanding ring 38 having finger engaging projections 39 and receivable within a groove 40 in the cylinder is utilized to detachably secure said latter member to the head 36. The lower end 41 of the cylinder 37 is adapted to lie closely adjacent the bottom of chamber 17. In the lower portion of the vertical wall of the cylinder are provided a number of spaced holes 42. The cleaning agent, which in the present instance is a fluid, is placed in the bottom of the chamber 17 and rises to a level about the holes 42 so that an air cell is established between the interior of the cylinder 37 and the vacuum conduit 20.

The holes 42 referred to above are spaced around the periphery of the cylinder wall and serve to evenly distribute the inrushing dirt-laden air into the fluid surrounding such cylinder. Hence the cleaning element is permitted to function in a very efficient manner. Also the size and number of the holes 42 may be varied to provide more or less resistance to the air being drawn through the cleaning fluid.

43 Positioned within the cylinder 37 is a float 43 consisting of an annular ring of cork or other buoyant material and one or more layers of screen 44. This float conforms in size to the inner dimension of the cylinder and is prevented from falling beneath the level of the uppermost of the holes 42 by the annular shoulder or rib 45 provided on the inner side of such cylinder. In operation the float just described serves to prevent any large particles of dirt from entering the fluid in the lower end of the cylinder; the mesh of such screen being smaller than the diameter of holes 42. As seen from Fig. 1, the cylinder 37 is considerably smaller than the inner diameter of the chamber 17 and the greater bulk of the liquid is confined in the annular pocket between such members. A float 46 in the form of a ring is positioned on the top of the column of liquid between the cylinder 37 and chamber 17.

In the operation of the present novel device the air drawn through the conduit 32 is passed downwardly through the tube 31 into the upper portion of cylinder 37 where the particles of dirt too large to pass through the holes 42 are separated by the screen 44. From there the air passes downwardly through the liquid in the lower end of the cylinder where still more of the dirt is removed from the air column, after which time the air passes outwardly through the openings 42 into the liquid surrounding such cylinder. In the process of passing the air through the liquid in the cylinder 37 and in the chamber 17, it is found that the dirt is thoroughly agitated and emulsified in such liquid. The float 46 serves to aid in breaking up the air bubbles which strike its under side and to evenly distribute the flow of air through the liquid around its inner and outer peripheries.

Baffle plate 47 may be employed at the upper end of the chamber to collect and break up any liquid containing fog or spray which is formed by the passage of air through the liquid and allow the same to return to the chamber and flow over this plate and then down the walls of the outer container. The baffle plate is shown in the form of a metallic plate provided with an upturned flange 48 fitting the upper portion of the recess 16 and having a central opening 49 of slightly larger diameter than that of the tube 31 passing therethrough.

It has also been previously mentioned that one of the objects of this invention is to construct the chamber 17 of transparent material. In the embodiment illustrated in the drawing, the chamber 17 is indicated as being formed of glass through which the interior thereof may be visible to determine the condition of the liquid carried therein. When this liquid is seen to be very clouded or thickly emulsified by the dirt coming through the conduit 32, the thumb screw 25 is loosened and the chamber may be unscrewed from its mounting and the liquid changed. During this process, the ring 38 is compressed and the cylinder 37 removed for suitable cleaning.

In Figs. 3 and 4 is illustrated an improved type of suction nozzle to be utilized in connection with the device described above. To the end of flexible hose 32 is secured a hollow connection 50 which serves as a handle for the vacuum nozzle 51 formed integrally therewith. The nozzle 51 is of conventional shape having an increasing area from the opening in the handle 50 to the lower end 52 thereof. In such lower end 52 is mounted a cylindrical agitating brush 53. The axis of such brush is formed by a twisted wire which has its ends 54 received in holes 55 in the sides of the nozzle 51. Screws 56 are used to lock such brush in any desired rotative position. A portion of the brush extends below the con-

tacting surface of the nozzle and as this portion becomes worn, the screws 56 are loosened and an unused portion of the flush is positioned to extend below the nozzle.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In apparatus of the character described, the combination of a chamber adapted to receive liquid therein and having a discharge port, a second chamber also adapted to receive liquid and mounted within said first-named chamber and having a closed bottom and a multiplicity of small openings in its lateral walls, an inlet conduit connected to said inner chamber, a float disposed in said first-named chamber and substantially closing the end of the space between said inner and outer chambers, and a baffle mounted between the surface of said liquid and said discharge port to prevent the discharge of liquid through said port.

2. In apparatus of the character described, the combination of a chamber adapted to receive liquid therein and having a discharge port, a second chamber also adapted to receive liquid and mounted within said first-named chamber and having a closed bottom and a multiplicity of small openings in its lateral walls, an inlet conduit connected to said inner chamber, and an imperforate float disposed in said first-named chamber and substantially closing the end of the space between said inner and outer chambers.

3. In apparatus of the character described, the combination of a chamber adapted to receive liquid therein and having a discharge port, a second chamber also adapted to receive liquid and mounted within said first-named chamber and having a closed bottom and a multiplicity of small openings in its lateral walls, an inlet conduit connected to said inner chamber, a float disposed in said first-named chamber and substantially closing the end of the space between said inner and outer chambers, and a second float mounted in said inner chamber and carrying a screen through which air from said inlet conduit must pass before contacting said liquid.

4. In apparatus of the character described, the combination of a chamber adapted to receive liquid therein and having a discharge port, a second chamber also adapted to receive liquid and mounted within said first-named chamber and having a closed bottom and a multiplicity of small openings in its lateral walls, an inlet conduit connected to said inner chamber, a float disposed in said first-named chamber and substantially clos-

ing the end of the space between said inner and outer chambers, a second float mounted in said inner chamber, said second float comprising an annular ring of cork, or the like, fitting closely within said inner chamber and carrying a disk of foraminous material, and a shoulder within said inner chamber adapted to prevent said second float from falling below the level of the uppermost of said small openings.

Signed by me, this 11th day of December, 1926.

HERMAN C. LINN.
